(57) **CLAIM**

The ornamental design for a tablet dock, as shown and described.

DESCRIPTION

FIG. 1 shows a front right perspective view of a tablet dock.

FIG. 2 shows a front elevational view of the tablet dock.

FIG. 3 shows a back elevational view of the tablet dock, with elements in dashed lines forming no part of the claimed design.

FIG. 4 shows a left side elevational view of the tablet dock, with elements in dashed lines forming no part of the claimed design.

FIG. 5 shows a right side elevational view of the tablet dock, with elements in dashed lines forming no part of the claimed design.

FIG. 6 shows a bottom plan view of the tablet dock.

FIG. 7 shows a front right perspective view of the tablet dock with an associated tablet docked in said tablet dock, with elements in dashed lines forming no part of the claimed design.

FIG. 8 shows a front elevational view of the tablet dock with the associated tablet docked in said tablet dock, with elements in dashed lines forming no part of the claimed design; and, FIG. 9 shows a top front perspective view of the tablet dock with the associated tablet, said associated tablet in the process of being docked by sliding along rails included on the tablet dock, with elements in dashed lines forming no part of the claimed design.
